UNITED STATES PATENT OFFICE.

JAKÓB CZECHOWICZ, OF TERRE HAUTE, INDIANA.

SELF-PROPELLING INVALID-CHAIR.

1,297,449.

Specification of Letters Patent. Patented Mar. 18, 1919.

Application filed July 15, 1918. Serial No. 244,997.

To all whom it may concern:

Be it known that I, JAKÓB CZECHOWICZ, a subject of the Emperor of Austria, residing at Terre Haute, in the county of Vigo and State of Indiana, have invented certain new and useful Improvements in Self-Propelling Invalid-Chairs, of which the following is a specification.

This invention relates to invalid chairs and more particularly to a self-propelled invalid chair, the object thereof being to provide a wheeled chair having a propelling device adapted to be wound and then released and controlled, for propelling the chair, suitable steering means being provided for controlling the direction of travel of the chair.

With the above and other objects in view as will appear as the description proceeds, the invention comprises the various novel features of construction and arrangement of parts which will be more fully described herein and set forth with particularity in the claims appended hereto.

Reference is had to the accompanying drawings forming a part of this application, in which like reference characters indicate the corresponding parts throughout the several views of the drawings and wherein,

Figure 1 is a side elevation of my improved self-propelled invalid chair,

Fig. 2 is a plan view thereof partly broken away, and

Fig. 3 is a side elevation of the opposite side from that shown in Fig. 1 of the drawings.

Referring to the drawings in detail, my improved chair is shown as comprising a bottom frame 10 preferably of rectangular formation and upon which is supported in spaced relation, a frame 11 carrying a seat portion 12 having side arms 13 and a back 14 which may be provided in connection with the seat, with the usual cushions 15. At the front, the seat is provided with an inclined foot rest 16 so as to add to the comfort of the invalid.

The bottom or supporting frame 10 projects rearwardly of the seat frame so as to pivotally support a steering wheel 17, said wheel having the usual fork and steering post 18, which post is also turnable in a bearing 19 supported above the rear portion of the bottom or supporting frame through the medium of two transversely spaced lon-

gitudinal braces 20. At its upper end, the steering post is provided with an arm 21 having connection through an angular rod 22 with a rack bar 23 arranged horizontally at one side of the chair and adapted to be shifted by rotation of a pinion 24, the crank handle 25 of which is journaled in a bearing 26 suspended from the adjacent arm of the chair. The rod 22 is designed to slide in a guideway 27 arranged at one side of the seat frame and also in a hanger 28 suspended from said arm, so as to accommodate the rear portion of the rack bar 23. Thus it will be seen, that by turning the crank handle 25, the rack bar can be shifted longitudinally so as to swing the arm 21 and thereby turn the steering wheel on its pivot for directing the chair in the desired course.

At the forward portion of the chair, are provided transporting and driving wheels 29 adapted to coöperate with the steering and transporting wheel 17, said wheels being suitably journaled on the bottom frame 10 and carrying sprocket wheels or pulleys 30. At the rear portion of the frame is arranged a spring motor 31 having a winding shaft 32 extending laterally to one side of the chair, namely, the opposite side from that to which the steering means is applied. At the outer end of the shaft 32 there is provided a pinion 33 meshing with a pinion 34 fixed to the lower end of an inclined shaft 35 journaled in the side frame portions. The upper end of the shaft carries a bevel gear or pinion 36 designed to be rotated for rotating the shaft 35 through the instrumentality of a larger bevel gear or pinion 37 journaled in the arm opposite to that carrying the steering means and designed to be rotated through the medium of a crank handle 38 for winding the motor.

The motor is provided with a transverse drive shaft 39 journaled in the bottom frame, the outer end thereof carrying sprocket wheels or pulleys 40, around which end sprocket wheels or pulleys 30 are arranged endless drive belts or chains 41, so that when the shaft is driven through the operation of the motor, the front wheels 105 will be rotated in the desired direction for moving the chair forwardly. Suitable means may be provided for reversing the direction of the motor and the shaft 32 is provided with a brake 42 similar to the 110

brakes provided upon the rear wheels of bicycles, so that upon turning the gear wheel 37 backwardly, the brake will be applied to stop the vehicle. Also, by holding the handles 33 stationary, the device can coast, it being unnecessary to employ the motor.

From the foregoing description taken in connection with the accompanying drawings, it is thought that a clear and comprehensive understanding of the construction, operation and advantages of my invention may be had, and while I have shown and described the device as embodying a specific structure, I desire that it be understood that such changes may be made in said structure as do not depart from the spirit and scope of the invention as claimed.

Having thus described my invention, what I claim as new, and desire to secure 20 by Letters Patent, is:

1. A self-propelled invalid chair, comprising a bottom frame, a seat frame, a back arranged upon the seat, a foot rest at the forward portion of the seat, said bottom frame projecting rearwardly of the seat frame, arms for the seat frame, a steering wheel carried by the rearwardly projecting portion of the bottom frame, operating means carried by the frame for turning the steering wheel, a motor carried by the bottom frame, means for winding said motor, transporting wheels at the forward

portion of the frame, and drive connections between the motor and the transporting wheels.

2. A self-propelled invalid chair, comprising a bottom frame, a seat frame, a back arranged upon the seat, a foot rest at the forward portion of the seat, said bottom frame projecting rearwardly of the seat frame, arms for the seat frame, a steering wheel carried by the rearwardly projecting portion of the bottom frame, a bearing supported in spaced relation above the bottom frame to receive the steering post of the steering wheel, an arm on said post, a rack bar slidably carried by one arm, means for shifting the rack bar and including a crank handle having a pinion, an angular rod connection between the rack bar and the arm, spaced longitudinal brace bars carried by the bottom frame, a spring motor carried by said brace bars, a winding shaft for said motor, operating means arranged upon the other arm having geared connection with said winding shaft for rotating the latter to wind the motor, a brake associated with the motor, transporting wheels journaled at the forward portion of the bottom frame and drive connections between said transporting wheels and the drive shaft of the motor.

In testimony whereof, I affix my signature hereto.

JAKÓB CZECHOWICZ.
